(57) **CLAIM**

The ornamental design for a cell culture apparatus, as shown and described.

DESCRIPTION

FIG. 1 is a perspective view of a cell culture apparatus showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view taken along lines 8-8 of FIG. 2; and,

FIG. 9 is a perspective cross-sectional view taken along lines 9-9 of FIG. 2.

The broken lines in the drawings illustrate portions of the cell culture apparatus that form no part of the claimed design.
